UNITED STATES PATENT OFFICE.

VINCENT G. ANDERSON, OF THIEF RIVER FALLS, MINNESOTA, ASSIGNOR TO
FREDERICK C. AUSTIN, OF CHICAGO, ILLINOIS.

PROPELLING APPARATUS.

1,242,635.

Specification of Letters Patent.

Patented Oct. 9, 1917.

Application filed August 19, 1916. Serial No. 115,766.

To all whom it may concern:

Be it known that I, VINCENT G. ANDERSON, a citizen of the United States of America, and resident of Thief River Falls, Pennington county, Minnesota, have invented a certain new and useful Improvement in Propelling Apparatus, of which the following is a specification.

My invention relates to propelling apparatus which is adapted more particularly for use in connection with excavating machines or other heavy structures that require moving ahead from time to time during the operation thereof.

Generally stated, the object of my invention is to provide an improved apparatus of this kind having means for raising the excavator or other heavy structure, and in which the further operation of the lifting means, after the weight of the excavator or other structure has been temporarily transferred from its own runways or other supporting means to a traveling support, will then shift the excavator or other structure forward.

It is also an object to provide certain details and features of construction and combinations tending to increase the general efficiency and desirability of a propelling apparatus of this particular character.

To the foregoing and other useful ends, my invention consists in matters hereinafter set forth and claimed.

In the accompanying drawings:

Fig. 1 is a plan of an excavator body provided with a propelling apparatus embodying the principles of my invention.

Fig. 2 is a side elevation of the structure shown in Fig. 1.

Fig. 3 is a transverse section on line 3—3 in Fig. 2.

Fig. 4 is an enlarged side elevation of a portion of said apparatus.

Fig. 5 is a plan of the device shown in Fig. 4.

As thus illustrated, the excavator body A may be of any suitable, known or approved character, and is provided with supporting runners or shoes α , at the four corners thereof, whereby it is adapted to rest on the ground during the excavating operation. It will be understood that the excavating apparatus (not shown) can be of any suitable character.

Between the side beams 1 and 2, at each

side of the body A, a supporting frame B is disposed upright and provided with a shoe b which rests on the surface of the ground. A small frame or cage C is also provided at each side of the excavator body, in position 60 to embrace the inclined upright 3 of the frame B, and is provided with rollers 4, 5, 6 and 7 to engage the body frame A, in a manner that will be readily understood. Each frame C has a small triangular element X which is pivoted on the axis of the rollers 7 and which is provided with rollers α to bear against the front side of the upright 3 when the excavator is moved forward. With this construction, the small frames or cages C can shift up and down on the inclined uprights 3 of the frame B, and the body-frame A can shift longitudinally in the said frames or cages C, during the operation of raising and lowering the 70 body-frame. For this purpose, the frames B are each provided with sheaves 8 and 9, near the top thereof, and each frame or cage C is provided with sheaves 10 and 11 at the front and rear upper corners thereof. The 75 rollers 4 and 5 are on the axes of the sheaves 11 and 10, respectively, it will be seen, and support the carrier C on the body, which permits freedom of motion and prevents binding of the relatively movable parts. 80 The cable D has its opposite ends secured at 12 to the frames or cages C, and then extends upward over the sheaves 9, downward around the sheaves 10, upward and over the sheaves 8, and then downward and under the sheaves 11, thus forming a powerful 85 lifting apparatus. The said cable extends around the sheaves 13 and 14 on the rear end of the excavator body A, and the middle portion of this cable extends around the 90 pulley E, which latter is connected with the pulley F around which travels the cable f of the winding drum G, the other end of this cable f being attached to the excavator body at 15, whereby the operation of said 95 drum in the direction to wind up the cable f causes a tightening of the cable D and a consequent lifting of the body-frame A, in a manner that will be readily understood. This lifting action can be carried out to any 100 sufficient extent, the object being to relieve the shoes or runners α of the weight of the body-frame, or at least to substantially reduce the weight thereon. In doing so, the weight is transferred from these shoes α 110.

to the shoes *b* of the supports *B*, and a continued operation of the cable *D* exerts a forward pull on the rear end of the excavator body-frame *A*, causing it to shift forward 5 on the rollers *6* and *7*, in a manner that will be readily understood. Then the body-frame *A* is lowered to the ground.

The means for pulling the frames *B* forward is as follows: The cable *H* has its opposite ends attached at *h* to the bases of the frames *B*, and said cable travels around the sheaves *16*, *17* and *18* on the front end of the body-frame *A*, the middle portion of this cable being attached at *19* to the shank of 10 the pulley *20*, which latter engages the cable *I* which has one end portion wound on the drum *i* and its other end attached at *21* to the excavator body-frame. With this arrangement, and by operating the drum *i* 15 after the excavator body-frame is lowered to the ground, the cable *H* will be tightened to pull the frames *B* forward on the ground. During this operation, the frames or cages *C* slide forward on the sides of the excavator body-frame. After this is done, the 20 lifting apparatus is again ready for operation, so that the body-frame *A* can be given another movement forward. Thus the frame *A* and the frames *B* take turns, so to speak, in moving forward, the frame *A* moving forward while the weight is on the frames *B*, and the said frames *B* being 25 shifted forward when the weight is on the frame *A*, thus accomplishing the desired movement forward from time to time during the excavating operation.

I do not limit myself to the exact construction shown and described.

What I claim as my invention is:

40 1. In a propelling apparatus for intermittently shifting a heavy body along the ground, a frame adapted to rest on the ground, a carrier movable up and down on said frame, rollers on said carrier to support said body, sheaves on said carrier, sheaves on said frame, a cable engaging all of said sheaves, means to secure one end of said cable to the front portion of said carrier, so that a pull on said cable will raise said carrier, and means on said body to operate said cable and thereby pull the body forward on said carrier.

45 2. The said structure, as specified by claim 1, having rollers to support the carrier on said body, in which means are provided for permitting said carrier to tilt with the body

without causing the cable to bind on said frame.

50 3. The said structure, as specified in claim 1, having rollers to support the carrier on said body, in which said frame is inclined forward, and in which said cable has the upright portions thereof also inclined forward.

4. The said structure, as specified in claim 65 1, in which the front end of said carrier has a pivoted element to engage said frame.

5. In a propelling apparatus for intermittently shifting a heavy body along the ground, a frame adapted to rest on the ground, a carrier movable up and down on said frame, rollers on said carrier to support said body, sheaves on said carrier, sheaves on said frame, a cable engaging all of said sheaves, so that a pull on said cable will 70 raise said carrier, means on said body to operate said cable and thereby pull the body forward on said carrier, and means for permitting said carrier to tilt with the body without causing the cable to bind on said 75 frame.

6. In a propelling apparatus for intermittently shifting a heavy body along the ground, a frame adapted to rest on the ground, a carrier movable up and down on 85 said frame, rollers on said carrier to support said body, sheaves on said carrier, rollers on the axes of said sheaves to support the carrier on said body, sheaves on said frame, a cable engaging all of said sheaves, so that a pull on said cable will 90 raise said carrier, and means on said body to operate said cable and thereby pull the body forward on said carrier, said frame being inclined forward, and said cable having the upright portions 95 thereof also inclined forward.

7. In a propelling apparatus for intermittently shifting a heavy body along the ground, a frame adapted to rest on the ground, a carrier movable up and down on 100 said frame, rollers on said carrier to support said body, sheaves on said carrier, sheaves on said frame, a cable engaging all of said sheaves, so that a pull on said cable will 105 raise said carrier, and means on said body to operate said cable and thereby pull the body forward on said carrier, the front end of said carrier having a pivoted element to engage said frame.

Signed by me at Chicago, Illinois, this 110
31st day of July, 1916.

VINCENT G. ANDERSON.
